CLAIM

The ornamental design for a cutter for electric shaver, as shown and described.

DESCRIPTION

FIG. 1 is a front elevational view of a cutter for electric shaver showing my new design; the rear elevational view being a mirror image;

FIG. 2 is a top plan view thereof;

FIG. 3 is a right side elevational view thereof; the left side elevational view being a mirror image;

FIG. 4 is a bottom plan view thereof;

FIG. 5 is an isometric view seen from the top thereof; and,

FIG. 6 is an isometric view of the bottom thereof.
The unshaded areas inside the central circular outline on the top surface and the rectangular outline on the bottom surface form no part of the claimed design.
